Patented Mar. 17, 1970

216,885

CIRCULATOR FOR A HEATER

Paul Andre Guinard, Avenue de Fouilleuse,
Saint-Cloud, France

Filed May 15, 1968, Ser. No. 11,954

Term of patent 14 years

Int. Cl. D23—03, 04
U.S. Cl. D23—73

FIG.1

Des. 216,885

PAGE 2

FIG.2

FIG. 3

FIG. 5

FIG. 4

FIG. 1 is a front view of a circulator for a heater showing my new design.

FIG. 2 is a side view thereof.

FIG. 3 is a side view of the side opposite FIG. 2.

FIG. 4 is a top plan view thereof.

FIG. 5 is a perspective view thereof on a reduced scale.

The rear of the circulator is substantially plain in appearance.

I claim:

The ornamental design for a circulator for a heater, as shown and described.
